OVERSHOE OR GALOSH

Joaquin de Noronha, Rio de Janeiro, Brazil

Application October 2, 1935, Serial No. 43,166
In Brazil November 1, 1934

5 Claims. (Cl. 36—7.3)

The present invention refers to improvements in rubber overshoes with the aim to avoid inconveniences existing in ordinary galoshes and at the same time to offer advantages of para-
5 mount importance, such as an automatic airing system.

It is a well known fact that when buying galoshes, one should not choose a loose-fitting pair because after a short time of wear they already
10 begin to widen and easily slip off in walking. It is therefore necessary always to buy rather tight-fitting ones. The effects resulting from such a tight fit on the toes and joints especially are only too well known; besides burning, fatigue
15 and perspiration of the feet, a general bodily indisposition is experienced owing to the fact that at every step the pressure on the joints causes friction which becomes more and more annoying the longer one walks. To all this, there must
20 still be added the complete exclusion of air from the shoe upper and the excessive weight of the overshoes. As regards the outward appearance of these overshoes, it is customary to finish them off with a coating of varnish so as to make them
25 appear uniform or also cover up surface flaws; but even then, they look antiquated and are not at all in harmony with modern shapes and styles of shoes.

The idea underlying the present invention is
30 to produce a galosh made intentionally too large for the shoe to be protected and which, despite this fact, will be accepted by the public without any reluctance.

Obviously, none of the evils mentioned above
35 can even come into existence with such an oversized galosh, because there will always be a fair space present between its upper and that of the considerably smaller shoe in it, so that the foot is no longer subjected to that harmful pressure which the common close-fitting overshoes naturally occasions. On the other hand, the
40 public will not use such an oversized galosh unless it is provided with an uncomplicated and efficiently functioning means for preventing it
45 from falling off the shoe in walking. Many will even object to wearing it if its large dimensions are not sufficiently disguised so as to look normal or if its upper becomes baggy for want of support and the shoe keeps on floating in it.

50 All these requirements are met by the improvements of the present invention, best applicable to an all-rubber, one-piece galosh, manufactured by the method, well known in the rubber industry, of pressing and vulcanizing in closed
55 steel moulds under high mechanical pressure.

The problem of retaining this oversized galosh in position on the shoe is resolved, according to the present invention, by moulding over the shaft a cover or web having a small aperture at the center as opening for the shoe; the resulting 5 broad web projecting from the top of the galosh towards the middle is a fastening device as simple as it is efficient. Further, the thin upper may be given sufficient stability as well as a very modern attractive appearance by adopting a surface of polygonal cross section. And finally, ventilation of the shoe may be effected by moulding air channels on the inner face of the web so as to renew the air confined by that web in the interspace between the upper of the galosh and 15 that of the much smaller shoe.

The basic principles of the present invention are more clearly set forth hereinafter, reference being made to the accompanying drawing, which illustrates one embodiment of the invention and
20 in which:

Fig. 1 is a plan view of the overshoe;

Fig. 2, a longitudinal section on the line II—II
of Fig. 1;

Fig. 3, a cross section on the line III—III of
25 Fig. 2;

Fig. 4, a side view showing the overshoe in
position on a shoe.

Throughout the views the same reference numerals indicate the same or corresponding parts. 30

In the first place, the overshoe of the present invention has an entirely new shape, as will be immediately explained. Fig. 1 shows clearly the fastening device 6, the broad web between the lines a—b—c—d and e—f—g—k. Whereas, normally, the edge of the opening in the common overshoes is more or less at the line a—b—c—d, the aperture 8 of this galosh is formed by the line e—f—g—k and is, therefore, approximately half as small. Relative to the total width of the 40 galosh, a reduction of half in the opening is enormous but the efficiency of the grip of the web 6 is thereby greatly increased.

The manner in which the device works when the galosh is in position on the shoe is illustrated in Fig. 4. Being forced by the much larger shoe neck to rise and press on it conically, the web tends continuously to draw the whole galosh upwards against the sole of the shoe. In this position, its large upper will remain separated from the much smaller shoe upper to the extent of the difference in their sizes viz. the space h. There is, therefore, no possibility of the foot being squeezed or in any way constrained by the galosh. In passing, it is 55

to be noted that the pressure exerted by the web, due to its high degree of elasticity, is practically negligible, but even then it is chiefly restricted to the heel and tongue portions both relatively rigid and therefore least susceptible to transmitting that little pressure to the foot inside the shoe.

Although the problem of eliminating the squeezing of the foot is resolved as just described, the galosh may be further improved by adopting the special construction for its upper shown in the example of the drawing, which does away with the possible bagginess consequent upon the upper being of thin rubber and oversized, and improves the clumsy appearance which any relatively too large footwear otherwise produces. The improvement is obtained by making the surface of its upper comprise several flat surfaces 2 which form angles at their junctions 3; in other words, the cross section of its upper is no longer semicircular like that of other overshoes but polygonal in shape. This innovation has two advantages. First, professional men well know that rubber articles, vulcanized in closed molds under high mechanical pressure, permanently retain any angles which may have been produced during vulcanization and that no matter how much one tries to flatten out such angular formations by force thereafter, they recover their original shapes immediately such force ceases to act. Now, as the upper of the overshoe of the present invention consists of flat surfaces forming angles, which shape is obtained during the vulcanization in closed molds, it is clear that when such an overshoe is worn on a shoe several sizes smaller, it will still retain that shape independently of the shoe within it, which, being much smaller in size, does not provide sufficient support for the thin rubber upper of the galosh to prevent it from sagging or otherwise looking baggy. As a matter of fact, the largest size of this galosh could be used on the smallest shoe without causing any other inconvenience than the one which the additional length of such a footwear occasions. In any case, the web would keep it well gripped on the shoe because the aperture 8 is far smaller than the neck of the smallest shoe. In other words, the galosh of the invention can hardly be denominated by sizes as conventionally understood in the trade, because it all depends on the customer who decides what space h he prefers to have between the galosh and his shoe. Practice has shown that four graded sizes of this galosh are more than sufficient to cover the whole range of shapes used in the trade. This is, of course, a great advantage to the dealer compared with the trouble which he has with other galoshes of which he has to have in stock practically one size for each shape and size of the shoes carried by the trade. A second advantage obtained by the angular junctions 3 is that by choosing the right places for them, they can be made to look like shoe seams, a means very much used nowadays to enhance the stylish lines of modern shoes. As a matter of fact, an overshoe of the present invention is then very easily mistaken for a shoe. The example shows

the galosh with a moccasin effect, very much in fashion at present. The galosh in the drawing is shown with the rib-shaped thickenings 4, 6, and 8 on the inner surface of the overshoe which should preferably run longitudinally in the upper and the sole, and vertically in the counter. The ribs of the upper are more conveniently ribbon-shaped as at 4 so as to more suitably adapt themselves to the flexible leather of the shoe upper, whereas a half-round shape 5 and 9 is more adequate for the ribs of the sole and the counter. The use of such ribs is quite well known and no claims as to their novelty is here made. They are described here only because they serve to perfect the galosh in that first, they help very much whilst the overshoe is being slipped on or off for, in this they act like rails for the shoe to slide on and thus prevent it from sticking as otherwise would happen considering the adhesive nature peculiar to rubber surfaces; secondly, and of equal importance, it is a fact that these ribs maintain the overshoes and the shoe spaced from each other at those points where the two unavoidably press together, for instance, at the sole, at the top-cap etc., thereby permitting the air to better circulate in the space h thus provided between the two.

Manifestly, variations may be resorted to and features used without others. Having thus described the invention, I claim:

1. A rubber galosh adapted to be put upon the outside of a leather shoe and comprising the combination, with a sole portion, of an oversized upper which is maintained out of contact with the vamp of said shoe when the galosh is in position on the shoe, and a web of live resilient rubber upon said oversized upper disposed across the top of the shaft thereof, said web having an aperture at the middle approximately half as large as the aperture in a conventional or known type of galosh.

2. A galosh according to claim 1, wherein the upper has a polygonal cross section.

3. A galosh according to claim 1, wherein the upper comprises a series of adjoining flat surface portions mutually disposed in cantilever formation against each other.

4. A rubber galosh adapted to be put upon the outside of a leather shoe and comprising the combination, with a sole portion, of an oversized upper having a converging web of live resilient rubber which at the top of said upper covers over from all sides the conventional opening or entrance usually found in known types of galoshes, said converging web being formed with an aperture at the middle which is less than one half of the width of the sole portion beneath the same.

5. A rubber galosh according to claim 4, wherein the upper comprises a connected series of adjoining surface portions of straight line cross sections which mutually form obtuse angles about a common arc scribed from a center beneath said upper, and are tangentially disposed with respect to said arc.

JOAQUIN DE NORONHA.
